United States Patent Office

Des. 211,212
Patented May 28, 1968

211,212

PAYROLL COMPUTER OR THE LIKE

Walter Schaffer, 202—19 45th Drive,
Bayside, N.Y. 11361

Filed July 14, 1967, Ser. No. 7,807

Term of patent 14 years

(Cl. D64—11)

FIG. 1

FIG. 3

FIG. 2

FIG. 4

FIG. 1 is a plan view of the payroll computer or the like;

FIG. 2 is a front view thereof, the back being plain and unornamented;

FIG. 3 is a right side view thereof, the opposite side being substantially similar in appearance; and

FIG. 4 is a perspective view thereof.

I claim:

The ornamental design for a payroll computer or the like, substantially as shown and described.
